COMPARTMENTED NURSES' BAG

Emily Robinson, Colorado Springs, Colo.

Application May 2, 1955, Serial No. 35,778

Term of patent 14 years

(Cl. D87—5)

Fig. 1

Fig. 2

*Fig. 3**Fig. 4**Fig. 5*Figure 1 is a perspective view of a compartmented nurses' bag, showing my new design in closed position.

Figure 2 is a perspective view of my compartmented nurses' bag, showing the bag opened.

Figure 3 is a perspective view showing one section of my compartmented nurses' bag.

Figure 4 is a perspective view showing the uniform section of my compartmented nurses' bag detached.

Figure 5 is a perspective view of my compartmented nurses' bag showing the bag open and the removable tray drawn forward.

I claim:

The ornamental design for a compartmented nurses' bag, as shown.
